UNITED STATES PATENT OFFICE.

HENRY GOEDDERTZ, OF DENVER, COLORADO.

ENGINE-STARTER.

1,169,393.

Specification of Letters Patent. Patented Jan. 25, 1916.

Application filed July 27, 1915. Serial No. 42,191.

To all whom it may concern:

Be it known that I, HENRY GOEDDERTZ, a citizen of the United States, residing at Denver, in the county of Denver and State 5 of Colorado, have invented certain new and useful Improvements in Engine-Starters, of which the following is a specification.

This invention relates to improvements in fluid-driven engine starters, and its primary 10 object resides in providing mechanism of simple construction in which the admission of a motive fluid to a reciprocating piston imparts through the intermediary of a transmission mechanism of novel construction, a rotary motion to the shaft of an internal combustion engine which is thereby set in motion. The construction of the transmission mechanism permits of adjustment for placing the engine shaft in driving 15 relation to the piston which by its reciprocating movement, supplies to a reservoir the motive fluid subsequently used for its operation to start the engine, as stated hereinabove.

The above and other objects all of which 20 will fully appear in the course of the following description, I attain by mechanism of the character illustrated in the accompanying drawings, in the various views of which like figures are similarly designated, 25 and in which,

Figure 1 is a perspective view of the front end of an automobile showing my improved starting mechanism installed in operative relation to the engine thereof, Fig. 2, an 30 enlarged front view of the starter, Fig. 3, a longitudinal section taken along the line 3—3, Fig. 2, Fig. 4, a fragmentary section along the line 4—4, Fig. 3, drawn to a smaller scale, Fig. 5, a reduced sectional elevation of the starter showing a modified 35 construction of the adjustable means by which the members of the transmission mechanism are connected for coöperation, Fig. 6, a section taken along the line 6—6, Fig. 3, Fig. 7, a plan view of the cylinder 40 of the starter, Figs. 8, 9 and 10, sectional views of the operating valve which controls the flow of motive fluid to and from the cylinder, in the three positions to which it 45 is moved in the operation of the device, and Fig. 11, an enlarged section taken along the line 11—11, Fig. 3.

Referring more specifically to the drawings, the numeral 2 designates the front 50 part of an automobile including the radiator 3 and the dash-board 4, 5 the internal

combustion engine of the vehicle, and 6 the steering post of the same.

My improved starter comprises an upright cylinder 7 supported upon a crank case 8 with which it is rigidly connected, and closed at its top by a removable head 9. The crank case is preferably provided with a foot 10 for the support of the starter upon a surface beneath the hood of the vehicle 65 and in adjacency to the engine of the same as shown in Fig. 1. The head 9 is held in place on the cylinder by nuts 12 screwed upon the threaded extremities of four stud bolts 13 which are secured upon the crank 70 case exteriorly of the cylinder, and extend loosely through openings in an external flange of the head. The bolts are furthermore employed as a support for an adjustable countershaft-carrier 14 and a guide 75 sheave 15 as will hereinafter be more fully described.

Mounted for reciprocation in the cylinder is a piston 16 which by means of a pitman 17 is operatively associated with a crank 18 80 in the crank case 8. The crank is fixed at the inner end of a shaft 19 which is rotatably supported in a bearing 20 formed integral with and exteriorly of the crank-case and which at its outer end carries a sprocket 85 wheel 21.

Mounted for vertical adjustment upon the four bolts 13 is the before-mentioned carrier 14 which has a laterally projecting shaft 22 upon which a speed-reducing member of the 90 transmission mechanism is rotatably mounted. The carrier is held in its adjusted positions between nuts 23 which are screwed upon the bolts 13, and its shaft 22 is provided at its outer extremity with a cap 24 95 which performs the double function of securing the transmission member supported upon the shaft against longitudinal displacement, and of holding the end of a return spring hereinafter to be described.

The above-mentioned movement-reducing member, which will hereinafter be referred to as the secondary transmission member, comprises a sprocket pinion 25 of smaller diameter than the sprocket wheel 21 with 105 which it is connected by a chain 26, and a sheave 27 which through the medium of a belt 28 imparts a rotary motion to a smaller sheave 29 on the primary transmission member which is mounted for rotation upon the bearing 20 in which the crank shaft is supported. The last-mentioned transmission

member includes in integral relation to the sheave 29, a sprocket wheel 30 which by the use of a chain 31 is operatively connected with a corresponding wheel fixed on the shaft of the internal combustion engine, not shown in the drawings.

20 A clutch element the purpose of which is to secure the rotative continuity of the crank shaft and the primary transmission member in one direction, is composed of a ratchet wheel 32 formed integrally upon the hub of the sprocket wheel 21, and a plurality of pawls 33 which are pivoted within a recess 24 of the transmission member to engage by 25 gravity, with the ratchet teeth, as shown in Fig. 6 of the drawings.

23 The belt used to transmit the movement of the primary transmission member to the other is normally slack, and the secondary member rotates in consequence idly upon its shaft. To effect a driving action of the primary transmission member with relation to the other member through the instrumentality of the belt, the latter is tensioned to frictionally engage the two sheaves, by means 25 of a belt tightener composed of a grooved pulley 34 on the end of an arm 35 which is rotatably mounted upon the bearing 20 of the crank case, and is normally supported 30 upon a pin 36 projecting from the case. The belt-tightener is operated from the driver's seat of the automobile by adjustment of a hand-lever 37 on the steering post 6, which by means of a cord 38 running over 35 the before-mentioned guide-sheave 15 on one of the bolts 13, is connected with the arm 35.

40 Instead of the sheaves, belt and tightener hereinabove described for effecting a movement transmitting connection between the members of the transmission mechanism, a 40 friction-drive such as illustrated in Fig. 5 of the drawings, may be employed. The transmission members are in this construction provided with friction wheels 39 and 45 40 in the place of the sheaves 27 and 29, and an intermediate wheel 41 positioned to simultaneously engage the peripheries of the other wheels, is rotatably mounted upon the arm 35.

50 A resilient element which in the operation serves to return the crank-shaft to its normal position in which the crank is a few degrees off its upper dead center, consists of a rod 42 which is pivoted on a wrist 43 of the sprocket 55 wheel 30 and which slidingly extends through a bore in the before-mentioned cap 24 on the shaft 22. For the purpose of permitting the cap 24 to follow the movement of the rod during rotation of the sprocket wheel 21, it 60 has a limited oscillating movement on the shaft upon which it is mounted. The cap is to this end secured to the shaft by means of a split pin 44 which is driven through a transverse bore in the end of the shaft and 65 projects through aligned openings of larger

diameter in the cap which is loosely fitted on the shaft. A spring 45 coiled around the rod 42 rests at one of its ends upon the head of the rod which connects with the wrist 43, and it has at its opposite end a rectilinear extension 46 which is held in a bore of the cap 24 by means of a set screw 47. It will be seen that this arrangement presents a ready means for varying the tension of the spring by sliding its extension in either 75 direction through the bore of the cap after the set-screw has been loosened, and inasmuch as the rod on which the spring is mounted is normally in an upright position, the degrees of contraction and expansion of 80 the spring during rotation of the crank-shaft will be the same at opposite sides of the vertical passing through the axis of rotation.

85 The motive fluid which operates the starter, is preferably supplied from a body of air under pressure contained in a reservoir 48.

90 The mechanism hereinbefore described not only starts the engine by the compressed air obtained from the reservoir, but it also serves to supply air under pressure to the reservoir at any time its replenishment is required. With this end in view, the cylinder 7 is connected with the reservoir by a conduit 49 95 which is branched as shown in Fig. 7, to connect with two separate openings in the cylinder-head as at 50 and 51. One of the branches of the conduit contains an operating valve 52 the rotary plug of which has an arm 53 which by means of a rod 54 is attached to a lever 55 on the steering post 6, and the other branch contains a check valve 64 adapted to obstruct the flow of motive fluid through the branch into the cylinder 100 while permitting its flow in the opposite direction. The plug 63 of the operating valve which is of the three-way type, is adjustable to the three positions shown in Figs. 8, 9 and 10 to either connect the cylinder with the atmosphere through the medium of a port 56, as in Fig. 10, to connect the cylinder with the reservoir by means of ports 57 and 58 as in Fig. 8, or to close the opening 51 of the cylinder with which the port 57 connects, against the flow of air in either direction, as in Fig. 9.

110 An air inlet 59 in the cylinder head is normally closed by a check valve 60 which permits the inflow of air when the air contained in the cylinder is reduced to less than atmospheric pressure. A valve controlled branch 61 of the conduit 49 adjacent the reservoir is provided for the attachment of a tube when it is desired to use the air stored in the reservoir for different purposes, as for example, the inflation of the pneumatic tires of the vehicle wheels, and a pressure gage 62 connected with the conduit, is installed adjacent 115 the driver's seat of the vehicle, to indicate 120 125 130

the density of the fluid contained in the reservoir.

Having thus described the mechanical construction of my improved starter, its operation is as follows: When the starter is in its normal inactive condition, the crank-shaft being held in a position slightly off its upper dead center, maintains through the medium of the pitman 17, the piston in the position 10 it occupies at the end of its upward stroke. The operating valve is in the position shown in Fig. 10 in which it connects the interior of the cylinder with the atmosphere through the port 56. The check valve 60 on the cylinder is in consequence closed, and inasmuch as the belt tightener is in its normal position of rest, the belt 28 is slack. Now, when it is desired to start the engine whose shaft is by means of the sprocket-chain 31 operatively 20 connected with the crank shaft of the starter, the driver of the vehicle changes by adjustment of the lever 55, the position of the valve plug 63 to that illustrated in Fig. 8 in which the cylinder is in connection with the reservoir. The consequent introduction of air 25 under pressure into the upper end of the cylinder imparts a downward motion to the piston whose movement is through the medium of the pitman converted into a rotary movement of the crank shaft. The ratchet clutch compels the primary transmission member to rotate in conjunction with the crank shaft, and the rotary movement of the said member is by means of the sprocket 35 chain 31 communicated to the shaft of the engine which in consequence is set in motion. In this connection it should be understood that the operator immediately after moving the lever 55 for the adjustment of the valve 40 plug to establish communication between the cylinder and the reservoir, returns the same to its original position so that after the piston has completed its downward stroke and the crank shaft has rotated through approximately one-half a revolution, the exhaust of 45 the compressed air through the port 56, permits the spring which was tensioned during the operation, to return the parts to their original position. By moving the operating 50 lever back and forth, the operation can in this manner be repeated as often as required, so that in case the first movement of the engine-shaft fails to produce the desired effect, it can be rotated intermittently until the engine 55 is set in motion. While the vehicle engine is in operation the primary transmission member rotates idly upon its bearing, the pawls of the clutch being by centrifugal force held in a position against the periphery of the recess in the transmission member, free from contact with the ratchet wheel on the sprocket wheel 2.

To replenish the reservoir by the operation of the starter, the valve is moved to the 65 position illustrated in Fig. 9 in which the

opening 51 in the cylinder-head is closed. The belt tightener is subsequently operated by adjustment of the lever 37 with the result that the rotary movement of the primary transmission member imparted thereto by 70 rotation of the engine-shaft, is communicated to the secondary transmission member, which in turn imparts a rotary movement to the crank shaft through the intermediary of the sprocket-chain 26. The reciprocating movement thus imparted to the piston alternately draws air of atmospheric pressure into the cylinder past the check valve 60, and drives the same through the opening 50 and past the check valve 64, into the reservoir. By 75 holding the two operating levers in their adjusted positions the operation of the air compressor may thus be continued until the air in the reservoir has been compressed to the required density which is indicated on the 80 pressure-gage 62.

The sprocket-wheels and sheaves of the transmission members, and the sprocket wheel on the engine-shaft are proportioned so that the speed of the piston is reduced 85 when the device is operated as a compressor, it being known that a compressor is most effective and economical when operating with a moderate velocity.

Having thus described the construction 90 and operation of my improved fluid-driven engine starter, I desire it understood that modifications in the relative arrangement and construction of parts may be resorted to within the spirit of my invention as defined in the appended claims. One variation, the substitution of a friction drive for the belt and pulley transmission, has been explained in the foregoing description. Changes in the construction and position of 95 the means for transmitting the movement of the crank shaft to the shaft of the automobile engine, naturally depend on the type of engine to which the invention is applied, and the position of the starter relative thereto, and if it is desired to use the device only as an engine starter, as for example in case a separate pump or air compressor is installed on the vehicle, the secondary transmission member and the sheave on the primary transmission member can be eliminated 100 and the check valves 60 and 64 on the cylinder-head omitted. The clutch can under these conditions be applied to the sprocket wheel on the engine shaft instead of to the 105 sprocket-wheel of the starter, thereby avoiding the continuous movement of the last-mentioned wheel while the engine is in operation.

By adjustment of the nuts 23 on the 110 screw bolts 13 the carrier may be moved to vary the distance between the center of its shaft and that of the crank shaft, or to change the tension of the spring in case its contraction by adjustment of the extension 115 120 125 130

46 in the bore of the cap has reached the limit determined by the length of said extension.

Having thus described my invention, what 5 I claim and desire to secure by Letters-Patent is:

1. An engine starter of the character described, comprising a piston chamber, a rotary element, a piston in the piston chamber 10 operatively connected with the said element, and mechanism to establish a driving connection between the said element and a rotary engine-shaft, including a primary transmission member, a clutch for the 15 conjunctive movement of the said transmission member and the said element in one direction, a secondary transmission member having a driving connection with the said element, a bearing for the said secondary 20 transmission-member, means for the adjustment of said bearing whereby to vary the distance between the axes of the members, and adjustable, normally inactive means for transmitting the movement of the primary 25 transmission-member to the secondary transmission member.

2. An engine starter of the character described comprising a piston-chamber, a support for said chamber, bolts on said support, 30 a head closing an end of the chamber, a rotary element, a piston in the piston chamber operatively connected with the said element, and mechanism to establish a driving connection between the said element and a rotary engine-shaft, including a primary 35 transmission-member, a clutch for the conjunctive movement of the said transmission member and the rotary element in one direction, a secondary transmission member having 40 a driving connection with the said element, a bearing for the said secondary transmission member, nuts on the said bolts adjustably securing said bearing, and adjustable, normally inactive means for transmitting 45 the movement of the primary transmission member to the secondary transmission member.

3. An engine starter of the character described, comprising a piston chamber, a rotary element, a piston in the piston chamber 50 operatively connected with the said element, and mechanism to establish a driving connection between the said element and a rotary engine-shaft, comprising a primary 55 rotary transmission member including a sheave, a clutch for the conjunctive movement of the said element and the said member in one direction, a secondary rotary transmission member in driving connection 60 with the primary transmission-member, and including a sheave, a belt on the said sheaves, and an adjustable belt-tightener to tension the belt.

4. In an engine starter of the character 65 described, a piston chamber, a rotary ele-

ment, a piston in the piston chamber operatively connected with said element, mechanism for transmitting the movement of the said element in one direction to a rotary engine-shaft, and resilient means for determining the normal position of the said element, composed of a rod having a wrist-connection with the element, an oscillating abutment in which said rod has a sliding motion, and a spring coiled around the rod in engagement with the abutment. 75

5. In an engine starter of the character described, a piston chamber, a rotary element, a piston in the piston chamber operatively connected with said element, mechanism for transmitting the movement of the said element in one direction to a rotary engine-shaft, and resilient means for determining the normal position of the said element, composed of a rod having a wrist-connection with the element, an oscillatory abutment in which said rod has a sliding motion, and a spring coiled around the rod 80 and adjustably secured to the said bearing at one of its ends. 85

6. An engine starter of the character described comprising a piston chamber, a rotary crank-shaft, a piston in the piston chamber in driving connection with the crank-shaft, mechanism for transmitting the movement of the said shaft in one direction, to a rotary engine-shaft, and resilient means for determining the normal position of the crank-shaft, composed of a guiding member 95 having a wrist connection with the crank-shaft, an oscillating abutment in which the guiding member has a sliding motion, and a spring guided by said member, in engagement with the abutment, the said guiding member being normally in a vertical position and holding the crank-shaft at a determinate degree off its dead center. 100

7. An engine starter of the character described comprising a piston chamber, a rotary crank-shaft, a piston in the piston-chamber in driving connection with the crank-shaft, mechanism to establish a driving connection between the crank shaft and a rotary engine-shaft, comprising a primary 110 transmission-member, a clutch for the conjunctive movement of the said member and the crank-shaft, and a secondary transmission-member in driving connection with the crank-shaft, a shaft supporting the secondary transmission member, a cap having an oscillating movement on the last-mentioned shaft, and resilient means for determining the normal condition of the crank-shaft, composed of a guiding member having a 115 wrist connection with the crank-shaft and a sliding connection with the said cap, and a spring guided by said member in engagement with the cap. 120

8. An engine starter of the character described comprising a piston chamber, a ro- 125

5 tary crank-shaft, a piston in the piston chamber in driving connection with the crank-shaft, mechanism to establish a driving connection between the crank shaft and a rotary engine-shaft, comprising a primary transmission-member, a clutch for the conjunctive movement of the said member and the crank-shaft, and a secondary transmission member in driving connection with the crank-shaft, a shaft supporting the secondary transmission member, a cap having an oscillating movement on the last-mentioned shaft, and resilient means for determining the normal condition of the 10 crank-shaft, composed of a guiding member having a wrist connection with the crank shaft and a sliding connection with the said cap, and a spring guided by said member, and adjustably attached to the cap at one 15 of its ends.

20 9. An engine starter of the character described comprising a piston chamber, a piston therein, mechanism for transmitting the piston movement to a driven element, means 25 for the adjustment of said mechanism whereby it operates to drive the piston by movement of the said element, a reservoir in connection with the piston chamber, a valve capable of making and breaking the 30 connection between the piston chamber and the reservoir and of connecting the piston chamber with the atmosphere, a second connection between the reservoir and the piston chamber, a valve normally closing said second connection and adapted to open for the 35 passage of air displaced by the piston-movement, to the reservoir, and a valve controlling an opening in the piston-chamber to admit atmosphere thereto when the air within 40 the cylinder is reduced to less than atmospheric pressure.

45 10. An engine starter of the character described comprising a piston chamber, a crank-shaft, a bearing in which said shaft

rotates, a piston in the piston chamber in 45 driving connection with the crank shaft, a transmission wheel fixed on the crank-shaft, a transmission-element rotating upon the bearing and including a member for its operative connection with a rotary engine 50 shaft, a clutch to automatically effect a conjunctive movement of the crank-shaft and the transmission element, a second shaft, a secondary transmission element rotating on the said second shaft and including a transmission-member in operative connection with the transmission member on the crank-shaft, a normally inactive device adapted to establish a connection between the transmission 55 elements for their conjunctive rotation, and means for the adjustment of said device to an operative position.

60 11. An engine starter of the character described comprising a piston chamber, a crank-shaft, a piston in the piston chamber 65 in driving connection with the crank shaft, a transmission wheel fixed on the crank-shaft, a rotary transmission element including a member for its operative connection with a rotary engine shaft, a clutch to automatically effect a conjunctive movement of the crank-shaft and the transmission element, a secondary rotary transmission element including a transmission-member in 70 operative connection with the transmission member on the crank-shaft, a normally inactive device adapted to establish a connection between the transmission elements for their conjunctive rotation, and means for the adjustment of said device to an operative 75 position.

80 In testimony whereof I have affixed my signature in presence of two witnesses.

HENRY GOEDDERTZ.
